CLAIM

The ornamental design for a seatbelt cutter with sheath, as shown and described.

DESCRIPTION

FIG. 1 is a left perspective view of a seatbelt cutter with sheath embodying the new design;

FIG. 2 is a right side elevation view of the seatbelt cutter with sheath;

FIG. 3 is a left side elevation view of the seatbelt cutter with sheath;

FIG. 4 is a top side elevation view of the seatbelt cutter with sheath;

FIG. 5 is a bottom side elevation view of the seatbelt cutter with sheath;

FIG. 6 is a front side elevation view of the seatbelt cutter with sheath; and,

FIG. 7 is a rear side elevation view of the seatbelt cutter with sheath.

The dotted lines depict aspects of the seatbelt cutter with sheath that form no part of the claimed design.

1 Claim, 5 Drawing Sheets
